UNITED STATES PATENT OFFICE.

GEORGE HORNELL THACHER, JR., OF NORTH PROVIDENCE, RHODE ISLAND.

DUMPING GRATE FOR STOKERS.

Application filed December 28, 1920. Serial No. 433,669.

To all whom it may concern:

Be it known that I, GEORGE H. THACHER, Jr., a citizen of the United States, residing at 1546 Smith Street, North Providence, in 5 the county of Providence, State of Rhode Island, have invented certain new and useful Improvements in Dumping Grates for Stokers; and I do hereby declare the following to be a full, clear, and exact description 10 of the invention, such as will enable others skilled in the art to which it appertains, to make and use the same.

My invention is an improvement in dumping grate for stokers of the character set 15 forth in my Patent No. 1,302,453, granted April 29, 1919, and the present application is a continuation in part of my prior application, Serial No. 353,423, filed January 23, 1920, and relates particularly to a construction 20 of dumping grate for such stokers.

The object of the invention is to provide a new and improved form of dumping grate structure, especially adapted for use in the stoker forming the subject-matter of the 25 above mentioned patent, wherein means is provided in connection with the structure for facilitating the repair thereof and for permitting the easy removal and replacement of parts of the structure which may become 30 broken or otherwise damaged.

In the drawings,

Figure 1 is a vertical section of the grate structure,

Figure 2 is a view similar to Figure 1, 35 but with the various detachable elements removed.

Figure 3 is an elevation of one of the detachable grate sections,

Figure 4 is top plan view of the same,

Figure 5 is a section taken along the line 40 5-5 of Figure 3,

Figure 6 is a section along the line 6-6 of Figure 1,

Figure 7 is a perspective view looking 45 from above showing a method of attaching the operating mechanism.

The improved dumping grate consists of an open substantially rectangular frame consisting of side members 1 which are rigidly 50 connected at one end by an integral curved shield 2, and at the other end by a bar 3. The shield 2 has openings 4 for permitting the passage of air to the fuel on the grate when the grate is being rocked, and the 55 shield and the crossbar 3 are connected by the grate sections shown more particularly in

Figures 3 and 4. Each of these grate sections is T-shaped in cross section, the body portion of the T forming a grate surface 5 for supporting the fuel, while the stem of the T is a fin depending from the center of the grate surface and having transverse holes or openings 7 for a purpose to be presently described. The forward end of the grate surface of each section is adapted to rest upon the upper edge of the curved shield 2, and referring to Figures 1 and 2 it will be seen that this edge is bevelled to fit the under face of the grate surface, which is curved upwardly at the forward end of the section. 70 The other end of the grate surface of the section rests on the crossbar 3, and it will be noticed referring to Figure 2, that the upper edges of the curved shield, and of the crossbar 3 are depressed below the upper edges of 75 the side members 1 of the frame, so that the upper faces of the grate section are flush with the upper edges of the side members.

The grate sections are held in place in the frame and on the shield and crossbar by 80 means of a rod 8, which is passed transversely through openings 9 in the side members, and through those openings of the series 7 of the fins which register with the openings 9. Near its ends the rod 8 has 85 openings through which are passed cotter pins 10 to prevent longitudinal movement of the rod. Referring to Figures 4, and 5, it will be noticed that the grate surface of each grate section has on each edge a series 90 of notches 11 which provide apertures through which the fine material formed by combustion may pass.

In order to permit the connection of mechanism for rocking the grate with the grate, 95 I provide openings 12 near the lower edge of the curved shield, and preferably near the center thereof, for receiving bolts 13 which connect a lug or arm 14 to the curved shield. This lug is notched or rabbeted to receive 100 the curved shield, and the bolts 13 are engaged by nuts 15 to rigidly connect the parts together. It will be noticed referring to Figure 2 that the openings 12 for the bolts 13 are reamed on the outer face of the shield, 105 to receive the heads of the bolts, in order that the said heads may be flush with the convex surface of the shield. This arm or lug 14 has an opening at the end remote from the shield for connection with a rocking mechanism of the character set forth in 110 my above mentioned prior patent. Each of

the side members 1 of the frame has intermediate its ends an outwardly extending trunnion 15, by means of which the grate may be mounted in the stoker.

- 5 In Figure 7 there is shown a grate in which the lug or arm 14 for connection with the rocking mechanism is dispensed with. In this arrangement the grate comprises the side members 16, the curved shield 17, and the crossbar 18, but intermediate the side members the crossbar and the shield are connected by an integral bar 19 which corresponds in general outline to the side member 16, but whose upper edge is flush with the tops of the crossbar 18 and the shield 17. The rocking mechanism for the grate is connected with the body of a yoke 20 whose arms engage opposite sides of the bar 19, and are pivoted thereto as indicated at 21. 10 It is preferable in many respects that the attachment of the rocking mechanism be in rear of the pivot mounting of the grate instead of in front as in Figure 1.

What I claim is:

- 25 1. A grate structure comprising a substantially rectangular open frame, and grate sections seated within the frame and detachably connected therewith, the frame comprising side members connected at one end by a curved perforate shield and at the other by a crossbar, the side members having trunnions whereby to rockably mount the frame, the grate sections being T shaped in cross-section, each comprising a grate surface and a depending fin, the detachable connection between the grate sections and the frame comprising a rod, the fins and the side members of the frame having registering openings for receiving the rod, and said sections resting at their ends on the curved shield and on the crossbar.

- 30 2. A grate structure comprising a substantially rectangular open frame, and grate sections seated within the frame and detachably connected therewith, the frame comprising side members connected at one end by a curved perforate shield and at the other by a crossbar, the side members having trunnions whereby to rockably mount the frame, the grate sections being T shaped in cross-section, each comprising a grate surface and a depending fin, the detachable con-

nection between the grate sections and the frame comprising a rod, the fins and the side members of the frame having registering 55 openings for receiving the rod, and said sections resting at their ends on the curved shield and on the crossbar, the grate sections having the edges of the grate surfaces serrated.

3. A grate structure comprising a substantially rectangular open frame, and grate sections seated within the frame, the frame consisting of side members provided with trunnions and connected at one end by a 60 curved perforate shield and at the other by a crossbar, the grate sections resting at their ends on the shield and on the crossbar, the said sections covering the upper edge of the shield and forming a guard therefor to prevent burning of the said edge, the sections being detachably connected with the frame, said frame having a bar intermediate the side members for connecting the grate structure with rocking mechanism.

4. A grate structure comprising side members provided with trunnions and connected at one end by a curved shield and at the other end by a bar, a plurality of grate sections, each composed of a vertical rib provided with apertures, and a grate surface at the top of and perpendicular to the plane of the rib, and having a flat portion supported at one end upon the bar and a curved portion supported at its other end upon the 80 upper edge of the shield and covering said edge and forming a guard therefor, said grate surface being provided with notches along each edge, and means passing through the side members and the apertures in the 85 ribs of the grate sections for holding the latter in place in the structure.

5. A grate structure comprising a frame composed of side members connected at one end by a crossbar and at the other by a 95 curved shield, the side members having trunnions whereby the frame may be mounted to rock, and grate sections detachably held in the frame and lapping upon the upper edge of the shield to provide for expansion and 100 contraction and to act as a guard for the said edge.

In testimony whereof I affix my signature.

GEORGE HORNEll THACHER, Jr.
